Patented Sept. 2, 1919.

UNITED STATES PATENT OFFICE.

CASSIUS M. BARTHOLOMEW, OF COLUMBUS, OHIO.

VEHICULAR TOY.

1,315,005.

Specification of Letters Patent.

Patented Sept. 2, 1919.

Application filed June 12, 1918. Serial No. 239,626.

To all whom it may concern:

Be it known that CASSIUS M. BARTHOLOMEW, a citizen of the United States, residing at Columbus, in the county of Franklin 5 and State of Ohio, has invented certain new and useful Improvements in Vehicular Toys, of which the following is a specification.

This invention relates broadly to toys, and has particular reference to an improved vehicle toy which is capable of being easily 10 and conveniently propelled, operated and guided, and one wherein lightness of weight and economy in manufacture obtains.

An object of the invention is to provide 15 an improved toy of this character wherein is embodied novel features of construction for effecting its guiding movements, when the same is being actively employed, and to this end use is made of a toy comprising a 20 wheel frame having a single, forwardly disposed steering wheel pivotally connected therewith, to provide a pair of spaced movable guide rails in connection with said frame to govern the steering positions of 25 said wheel, and which rails also are positioned so as to be capable of being conveniently grasped by one using the toy so that the user will be firmly positioned and braced upon the seat structure of the toy 30 and thus prevented from accidentally falling off.

A further object of the invention resides 35 in a toy vehicle wherein the parts are so constructed and arranged that the user may operate the vehicle while assuming one of a variety of positions, such as from a kneeling, reclining or an erect position, thus adding 40 to the general enjoyment affording properties of the vehicle and enabling the same to be successfully and conveniently propelled.

With these and other objects in view, as 45 will appear as the description proceeds, the invention accordingly consists in the novel features of construction, combinations of elements, and arrangement of parts herein- 50 after fully described and having the scope thereof defined by the appended claims.

In the drawing, forming a part of this 55 specification, and wherein similar characters of reference denote like and corresponding parts:

Figure 1 is a perspective view of the toy vehicle constructed in accordance with the preferred principles of the invention.

Fig. 2 is a bottom plan view of the ve-

hicle and disclosing by broken lines the steering action of the spaced guide rails.

Fig. 3 is a rear elevation of the vehicle, and

Fig. 4 is a top plan view of a slightly 60 modified form of the invention.

Referring more particularly to the details of the invention, my improved toy consists essentially of a body frame which includes a longitudinally extending, centrally disposed bar 1, which is provided contiguous to its rear end with a plurality of substantially resilient, bowl shaped arms 2. These arms are suitably spaced and extend upwardly in substantially the manner disclosed 70 in Fig. 3, and have their free ends connected in any suitable manner with a plurality of spaced longitudinally extending rods 3. Extending between the rods is a fabric seat member 4, upon which the user of the toy is 75 adapted to kneel or recline when the same is being actively employed.

Swivelly connected as at 5 and 6 to the front and rear ends of the bar 1 are a plurality of metallic braces 7, which have their free ends suitably mounted in slots 8 formed in guide rails 9, the latter extending longitudinally of the toy and in spaced relation from the seat structure. By virtue of this construction it will be seen that by grasping 80 the rails 9, the bar may be longitudinally shifted in the manner disclosed by broken lines in Fig. 2 of the drawing, and this shifting movement is employed in effecting the 85 steering of the vehicle.

To carry out this function, the forwardly disposed brace 7 is provided with depending bearing arms 10, which arms are adapted to oscillate about the forward pivot 5 when the rails 9 are longitudinally shifted. The 90 lower ends of the arms 10 are suitably apertured for the reception of a stud shaft 11, upon which is rotatably mounted a forwardly disposed steering wheel 12. From this it will be gathered that by longitudinally 95 moving the rails 9, the wheel 12 will be rotated about the swivel 5 in unison therewith, thus providing means for conveniently controlling the direction of movement of the vehicle.

A rigid yoke shaped bracket 13 is suitably carried by the rear end of the bar 1, and is independent, in this instance, of the shifting movement of the guide rails. The lower ends of this bracket are provided with alined 110

openings for the reception of a transversely extending shaft 14, this latter shaft being equipped with a pair of spaced rearwardly disposed balancing wheels 15, which in conjunction with the forwardly disposed wheel 12 substantially support the toy in an upright position, and prevent its tilting from side to side. Cotter pins 16 pass through the shafts 11 and 14 and serve to retain the wheels 12 and 15 in operative positions on said shafts.

From the foregoing it will be seen that there is provided a toy of extremely light weight and capable of being conveniently controlled and propelled. To effect the initial steering of the toy, the user may kneel with one knee upon the seat member 4 and with the free foot the vehicle is pushed or thrust forward. Then after the vehicle has gained considerable momentum or is running down hill the user may recline upon the seat 4 without exerting further effort. By reason of the location of the guide rails 9, the latter are in position to be conveniently grasped in order that the user will be firmly retained upon the seat structure, and these rails, as previously described, also have the dual purpose of controlling the direction of movement of the vehicle.

In Fig. 4 a slightly modified form of the invention has been disclosed. In this latter form, the vehicle consists of a plurality of rigidly mounted rods 16, which are stationarily supported by the bar 1, and across these rods extends the fabric seat member 4^a which in this modified form extends to the other rails, thus eliminating the use of the rods 3, which are employed in the preferred form. The forward ends of the rods 16 are of a tubular nature, and are adapted to receive telescopically mounted guide rails 17. The forward ends of these guide rails are connected in the manner described in the preferred form with the steering wheel 12^a, whereby upon the reciprocation of the guide rails the steering of the vehicle will be effected. This latter form may be advantageously employed on account of its economical construction, but its fundamental principles of construction as will be obvious are exactly similar with those of the preferred form.

I claim:

1. A toy vehicle comprising a body frame, a front and rear wheel structure for said frame, said body frame including a pair of hand rails extending longitudinally of the frame and shiftable longitudinally thereof, and means for operatively connecting said rails with said wheel structure so that steering movement is imparted to the same by the shifting of the rails.

2. A toy vehicle comprising a body frame, a front and rear wheel structure for said frame, said body frame including a hand rail structure longitudinally shiftable and disposed longitudinally with respect to said frame, and means for operatively connecting said rail structure with said wheel structure so that steering movement is imparted to the same by shifting said rail structure.

3. A toy vehicle comprising a body frame, a front and rear wheel structure for said body frame, said body frame including a hand rail structure longitudinally shiftable and disposed longitudinally of said frame, a seat structure carried by said frame and mounted thereon entirely independent of said rail structure, and means for operatively connecting said rail structure with said wheel structure so that steering movement is imparted to the same by shifting of said rail structure.

4. A toy vehicle comprising a longitudinally extending body frame, a pair of wheels supported adjacent the rear of said frame, a steering wheel structure operatively connected with the front end of said frame, a seat structure carried by said frame, a pair of longitudinally extending guide rails disposed on opposite sides of said frame, and means for operatively connecting said rails with the steering wheel structure in order to effect the operation of the latter and to thereby control the direction of movement of said vehicle.

5. A toy vehicle comprising a longitudinally extending body frame, a pair of wheels supported adjacent the rear of said frame, a steering wheel structure swiveled to the forward end of said frame, a pair of guide rails disposed longitudinally upon opposite sides of said frame, and means extending from said frame to support said rails and to permit said rails to impart steering movement to said steering wheel structure.

6. A toy vehicle comprising a longitudinally extending bar member, a pair of balancing wheels supported for rotation adjacent the rear of said member, a single steering wheel swiveled adjacent the forward end of said bar, a pair of guide rails disposed longitudinally on either side of said bar, means extending from said bar to support said rails and to permit their longitudinal movement, means operable upon the shifting of said rails to impart steering movement to said steering wheel, and a seat structure supported by said bar independently of said guide rails.

In testimony whereof I affix my signature.

C. M. BARTHOLOMEW.
